DESIGN FOR A TRACTOR

Theophilus Brown, Moline, Ill., and Henry Dreyfuss, New York, N. Y., assignors to Deere & Company, Moline, Ill., a corporation of Illinois

Application March 26, 1945, Serial No. 118,721

Term of patent 14 years

(Cl. D14—3)

To all whom it may concern:

Be it known that we, Theophilus Brown and Henry Dreyfuss, citizens of the United States, residing at Moline, in the county of Rock Island and State of Illinois, and at New York city, in the county of New York and State of New York, respectively, have invented a new, original, and ornamental Design for a Tractor, of which the following is a specification, reference being had to the accompanying drawings, forming a part thereof, in which

Figure 1 is a perspective view of the front and side of a tractor showing our new design.

Figure 2 is a side perspective view.

Figure 3 is a perspective view showing a side and rear of the tractor and

Figure 4 is a top plan view.

The dominant features of our design are shown in solid black lines in the drawings.

We claim:

The ornamental design for a tractor, as shown and described.

THEOPHILUS BROWN.
HENRY DREYFUSS.
